UNITED STATES PATENT OFFICE.

KARL JOHAN LJUNGBERG, OF STOCKHOLM, SWEDEN.

METHOD OF BUILDING REINFORCED CONCRETE STRUCTURES.

Application filed March 5, 1925, Serial No. 18,196, and in Sweden July 31, 1924.

This invention relates to an improved method of building concrete arch structures of the type having a metallic reenforcement consisting wholly or partially of tubes filled 5 with concrete and surrounded by a main concrete body.

Several methods of building concrete arches having tubular metallic reenforcement have been proposed, but generally such 10 methods have the drawback that the iron structures will be very heavy and expensive and that rather expensive scaffoldings or other supporting means must be used for supporting the iron structure and the concrete until the latter has set.

The chief object of this invention is to make it possible to use a light tubular metallic reenforcement in building arches of reinforced concrete.

20 A further object of the invention is to make it possible to use a light tubular metallic reenforcement in building arches of reinforced concrete.

A further object of the invention is to 25 make it possible to dispense with the use of scaffoldings or other provisional supporting means during the filling of the tubular metallic structure with concrete as well as during the moulding of the outer concrete 30 body and in this manner to obtain in each of the three main parts of the structure, namely tubes, concrete filling and the surrounding main concrete body, stresses which as far as possible correspond to the strength 35 of said parts.

With these objects in view, the invention consists, chiefly, in first erecting a light arched frame-work consisting chiefly of metal tubes and having a carrying capacity 40 adapted to support its own weight and the weight of a concrete mass filling the tubes, then utilizing said arched frame-work as the only supporting means during the filling of the tubes, and when said concrete filling has 45 set, finally utilizing the arched frame-work with its concrete filling as the only supporting means for moulds and concrete in moulding the main concrete body around the metallic frame-work.

50 In this manner I am able to build at low cost a reinforced concrete arch having a minimum of metallic reenforcement and the said reenforcement as well as the concrete included in the tubes will be loaded in the most effective manner. The method is especially adapted for building large bridges

in which the metallic tubular reenforcements hitherto proposed would be too heavy and expensive for practical use.

In the accompanying drawing I have 60 shown in Fig. 1 an elevation of a portion of an arched frame-work adapted to be used as reenforcement in an arched bridge of reinforced concrete and in Fig. 2 a cross-sectional view thereof with concrete moulded 65 around the reenforcement.

The reenforcement consists according to the present invention wholly or partly of circular iron tubes with a rather large diameter and a rather small thickness of the 70 walls. The total sectional area of the tubes is, however, small in comparison with the total sectional area of the arch as is clear from Fig. 2. In the constructional form shown in the drawing the tubes *a* form the booms or chords of the frame-work arch, the diagonal and vertical rods of which consist of iron plate or profile iron *b*. Said frame-work arch forms a skeleton of small weight as compared with the finished reinforced concrete structure and is first erected. The building of said skeleton can be performed in several ways. When the building ground is favorable the skeleton can be 75 built with the aid of a wood scaffold which on account of the small weight of the iron skeleton requires essentially smaller dimensions than if it should carry the whole concrete structure. Another method is to build the skeleton arch on the ground in two 80 halves which then are raised up in their positions by means of lifting machines and rotated about axes at their base ends whereupon the opposite ends are connected to each other, or it may be preferred, dependent on the circumstances, to build up the skeleton from the base ends as is sometimes usual in erecting arched bearing constructions of frame-work. Also other methods of erecting the light skeleton arch can be used.

When the iron skeleton has been erected in its place, it forms a provisional metallic arch standing free by itself and having a supporting capacity adapted to support a concrete mass sufficient to fill the channels 95 of the tubes. The tubes of said arch are now filled with concrete through suitable openings in the tube walls, the tube walls serving in this operation as moulds. When the concrete filling has set, the tube structure and on account thereof also the whole skeleton construction has obtained a highly 100 105 110

increased bearing capacity. The iron skeleton can, therefore, be made very light and notwithstanding after the filling of the tubes with concrete obtain a sufficient bearing power for the following moulding of the main concrete body. This result depends on this that the tubes filled with concrete are used essentially as chords or girths in the arch construction, in which the stress acts as compression and that concrete included in tubes has a rather great capacity for resisting pressure.

When the concrete in the tubes has set sufficiently, casings for the moulding of the final concrete arch are set up, said casings being carried only by the reenforced iron skeleton already erected. Then the main concrete body is moulded around the iron reenforcement in the usual manner in said moulds.

The method comprises accordingly three different steps of proceeding, viz:

1. The erecting of a light skeleton of iron in which all or some parts consist of tubes and having by itself a carrying capacity substantially sufficient to support its own weight and the weight of a concrete mass filling the tubes.

2. The utilizing of said metallic skeleton as only supporting means in filling the tubes with concrete.

3. The setting up of moulds and moulding the concrete body around the metallic structure by using the reenforced iron skeleton as the only supporting structure for the moulds and the surrounding concrete.

The filling of the tubes and the moulding of the heavy main structure can accordingly be performed without the use of expensive scaffolding. Furthermore, another result is attained. When the metallic arched frame-work has been erected its own weight causes in the metal an initial strain which is further increased when the tubes are filled with concrete in as much as said concrete is supported only by the tubular metallic arch. When said concrete has set and the main concrete body is moulded around the metallic frame-work the strains of the metal is still further increased and at the same time the concrete enclosed in the tubes receives its

initial strain. When also the outer concrete has set and the arch is loaded the outer main concrete body receives its strain while the strains of the metal reenforcement and of the enclosed concrete are further increased. The concrete enclosed in the tubes is thus subjected to greater stresses than the surrounding concrete. As concrete included in the tubes by the action of the tubes obtains the ability to sustain even larger pressures than concrete having spiral reenforcement the concrete included in the tubes will be utilized in a more economical manner in comparison with the case in which the whole concrete mass in a section is moulded simultaneously in moulds carried by an independent scaffold. In the latter case the concrete obtains even if it is reenforced by tubes or spiral irons the same stress in the tubes or inside the spiral reenforcement as immediately outside the same and as the outside concrete ought not to be loaded as much as the included one the reenforcement aimed at by the tubes or the spiral irons cannot be fully utilized. Also the iron used as reenforcement obtains according to this invention a final strain that is better suited to its strength than when the concrete body is moulded in moulds supported by an independent scaffolding, suspension ropes or the like.

What I claim is:

A method of building concrete arch structures, comprising first erecting a light arched frame-work consisting chiefly of empty metal tubes and having in itself a carrying capacity adapted to support its own weight; filling the tubes with a reenforcing concrete mass after erecting the frame-work said arched unfilled frame-work being the only supporting means during the filling of the tubes and when said concrete filling has set, utilizing the arched frame-work with its reenforcing concrete filling as the only supporting means for molds, and molding the main concrete body in said molds around the concrete filled tubes and metallic frame-work.

In testimony whereof I have signed my name.

KARL JOHAN LJUNGBERG.
